WORK SUPPORT FOR RIVETING MACHINES

Arthur R. Havener, Wayland, Mass., assignor to
 Judson L. Thomson Manufacturing Company,
 Waltham, Mass., a corporation of Massachusetts

Application November 20, 1934, Serial No. 753,854

13 Claims. (Cl. 218—2)

This invention relates to a work support which, although designed with special reference to use in riveting machines of the type shown and described in an application for United States Letters Patent for riveting machines filed by me November 20, 1934, Serial Number 753,853, is adapted for use in various other machines of that general class.

Generally in the use of riveting machines, it is customary for the operator to position the work by hand in proper position on a fixed work support and then to start the machine in operation to set the rivets by pressure on a foot treadle. When the work is of small size, however, there is great danger of injury to the hands of the operator through a premature starting of the machine or in the operation of the machine because of the proximity of the hands to the rivet driving tool. To avoid injury requires careful positioning and handling of the work which has the effect of slowing down the speed of operation and the amount of work turned out, thereby increasing the cost of production.

One of the important objects of the invention 25 is the provision of a work support for riveting and similar machines which is normally in an inoperative position for receiving and positioning the work and which is adapted to be moved into an operative position before the machine is started, thereby eliminating all danger of injury to the operator's hands.

Another object of the invention is the provision of means whereby the depression of the foot treadle usually employed to start the machine 35 first moves the work support from its normal position to an operative position before it functions to start the machine.

A further object of this invention is the provision of a work support of the above character 40 adapted for horizontal reciprocation from an inoperative to an operative position, and vice versa.

Other objects of the invention will be in part obvious and in part more particularly described hereinafter.

45 In the accompanying drawings illustrating one embodiment of my invention, Figure 1 is a left side elevation of a riveting machine having a work support constructed and adapted to be operated in accordance with my invention;

50 Fig. 2 is an elevation looking from left to right in Fig. 1 on an enlarged scale of the clutch mechanism of the machine;

Fig. 3 is a side elevation of the work support; and

55 Fig. 4 is a front elevation of the same.

In the drawings, there is shown only such parts of the riveting machine of my copending application hereinbefore referred to as are necessary for an understanding of the invention of this application and reference may be made to said application for a description of the parts of said machine not herein shown.

Referring to Figure 1 of the drawings, 12 indicates the frame of the machine mounted on a base 13 and having an upper overhanging arm 14. A rivet driver 15 is mounted in the lower end of a slide 16, rectangular in cross section, which is reciprocated in suitable ways in the arm 14 by a lever 17 pivotally connected at one end to the upper end of the slide. The lever 17 is pivoted on a pin 18 in an arm 19 pivotally mounted at its lower end on a pin 20 set in the frame 12. The rear end of the lever 17 is pivotally connected by a pin 21 to a member 22, which at its lower end is mounted upon a crank 23 of a shaft 24 rotatably mounted in the frame. The member 22 is made up of two parts having a screw-threaded engagement with each other permitting the length of said member to be increased or decreased at will.

On the extended base 13 of the frame is mounted a motor 30 having a shaft 31 provided with a worm gear 32 which meshes with a gear 33 fixed to a shaft 34 rotatably mounted in the frame 12. A pinion 35, also fastened to the shaft 34, meshes with an idler gear 36 adapted for free rotation on the shaft 24 which constitutes the driving member of a two part clutch for rotating said shaft, the other or driven member 37 of said clutch being fastened to the shaft 24.

The driving member 36 is recessed on one side and provided with a plurality of pins spaced at intervals around said recess, and the driven member 37, projecting into said recess, carries a pivotally mounted dog which is held by a spring-actuated pin in position for engaging one of said first-mentioned pins for locking the two parts of the clutch together in order to rotate the shaft 24. These parts are shown in detail in my companion application hereinbefore referred to, to which reference may be made for a more complete description.

The gear or driving member 36 is unlocked from the driven member 37 of the clutch by the slide 45 which is caused to engage the outer end 46 of the dog and move the same out of engagement with one of the pins carried by the driving member, which permits the driving member to rotate freely, while the driven member of

the clutch and the shaft 24 to which it is fastened, remain stationary.

The slide 45 is mounted for reciprocation in a suitable way formed in the frame of the machine and is provided with an outwardly projecting arm 47. A spring 48, constantly under tension, is attached at one end to said arm and at the other end to a pin 50 in said frame, which spring holds the slide in operative position for 10 engaging the end of the dog to disconnect the two parts of the clutch (Figs. 1 and 2).

For withdrawing the slide from engagement with the end of the dog 41 to permit the spring-actuated pin 43 to force the dog into engagement 15 with a pin 40 to lock the two parts of the clutch together to start the machine, suitable means, adapted to be operated by a foot treadle, is provided (Fig. 2). A lever 52 is pivotally mounted at its lower end upon a pin 53 set in the frame, 20 and fastened to the lever is a short lateral arm 54 operatively connected to a foot treadle by means hereinafter described. Pivotally mounted on a pin in the upper end of the lever 52 is a pawl 56 which is held in position for engaging 25 the arm 47 on the slide by a spring 57 under tension connected at one end to a pin 58 set in the tail of the pawl and at its other end to a hook 59 on the lever. The pin 58 serves also as a stop, engaging one side edge of the lever to 30 hold the nose of the pawl in operative position for moving the slide to the right when the lever is turned by depressing the treadle. In this operation, the nose of the pawl engages the arm and moves the slide to the right until the 35 tail of the pawl strikes a screw 60 threaded in a projecting lug 61 on the frame when the further movement of the lever causes the nose of the pawl to disengage from the arm on the slide, permitting the spring 48 to return the slide 40 instantly to operative position for disconnecting the two parts of the clutch at the end of one complete revolution. The screw 61 may be held in adjusted position by a set nut 62.

Fastened to the front face of the frame in 45 alignment with said upper arm is a lower arm 120 to which is secured a plate 122 projecting beyond the end of the arm. Fastened to this plate is a top plate 123 provided with a longitudinal recess 124 in its top face having dovetailed sides, 50 in which recess is slidably fitted the base 126 of a work support 127 carrying an anvil 128, having mounted therein a spring-pressed retractable pilot 130 for centering tubular rivets mounted thereon.

For moving the work support 127 inwardly 55 from a normally inoperative to an operative position in which the anvil is in alignment with the driver, any suitable means adapted to be operated by a foot treadle may be provided. One form of this means comprises a bell-crank lever 132 pivotally mounted on a pin 133 in the lower end of a depending plate bracket 134 fastened at its upper end to the lower arm 120 and plate 122. The upper arm of said bell-crank 60 lever 132 is pivotally connected by a pin 135 to one end of a link 136, the other end of which is pivotally connected by a pin 137 to a lever 138, which, in turn, is pivotally mounted at its lower end on a pin 139 in the bracket 134. The 65 upper end of the lever 138 is pivotally connected by a pin 140 to a short link 141, having its other end likewise connected by a pin 142 to a bifurcated lug 143 on the work support.

The lower arm of the bell-crank lever 132 is 70 pivotally connected by a pin 145 to an elongated

plate link 147 having a longitudinal slot 148 in its lower end. Connected to the link 147 by a block 150 and rod 151 is a foot treadle 152 pivotally mounted on a bracket 153 and normally held in raised position by a spring 157. The block 150 is bored to receive the rod 151 and is adjustably fastened thereto adjacent its upper end by a screw 154. In one end of the block is a pin 155 which projects through the slot 148 in the link 147 and is held therein loosely to permit the pin to slide in said slot by a washer 156. A spring 158 under tension, connected at its upper end to the pin 145 and at its lower end to the pin 155, tends to hold the pin in engagement with the upper end of the slot 151.

The block 150 is also bored to receive loosely the lower end of a rod 160 which, at its upper end, is hooked into arm 54, for operating the clutch to start the machine. Fastened to the rod 160 by a screw 161 is a collar 162 adapted to be engaged by the block 150 for starting the machine after the preliminary movement of the treadle has moved the work support into normal operative position. By adjusting the distance between the block and collar, the time of starting the machine in relation to the moving of the work support can be closely regulated. An adjustable screw stop 164 threaded into the rear face of the work support is adapted to engage an upwardly projecting lug 165 on the top plate 123 for limiting the rearward movement of the work support to secure alignment between it and the rivet driver. The rod 160 is normally held in a raised position by a spring 161 fastened at one end to a hook 168 set in the bottom of the base 13 and having its other end hooked around a pin 169 carried by the rod 160.

The rivets used in the machine are of the well-known tubular type and are fed to a rivet holder 170 from a hopper through a raceway 172, which parts are of construction well-known to those skilled in the art.

In the operation of the machine, a rivet is fed into the holder in position to be engaged by the driver on its downward stroke. Normally, the work support is in an inoperative position toward the operator, as shown in Figure 1, in which position the operator places the previously punched work upon the anvil, centering it by means of the spindle or pilot 130 in the punched hole. After the work has been properly positioned, the treadle is depressed, which pulls down the lower arm of the bell-crank lever 132 and through the instrumentality of the link 136, the lever 138 and the link 141, moves the work support rearwardly 55 until the stop 164 engages the lug 165. The spring 158 is of sufficient strength to resist this movement and to hold the pin 155 in the upper end of the slot 148 in the link 147. When further rearward movement of the work support is prevented by the stop 164, the block 150 is then pulled downwardly by the rod 151 against the tension of the spring 158 until it engages the collar 162, after which the continued depression of the treadle pulls the rod 160 downwardly to start the machine to set the rivet. Preferably, the collar 162 is so adjusted on the starting rod that after the work support has been moved to operative position, there is a very slight additional depression of the treadle before the block 60 150 engages said collar to start the machine.

The treadle is held depressed until the setting operation is completed. When the pressure on the treadle is released, it is raised by a spring, as shown in my companion application hereinbefore 75

referred to, and thereby the pin 155 in the block 150 engages the upper end of the slot in the link 147, pushes the link upwardly and operates the bell-crank lever to throw the work support into its normal inoperative position.

The clutch used in a machine of this type is a one-revolution clutch and the machine stops at the end of one revolution irrespective of the position of the rod 160 and it cannot again be started until the pressure of the treadle is released.

My invention entirely prevents injury to the operator's hands while positioning the work, which instills a sense of security and tends to speed up the work.

It is to be understood that the invention is not to be limited to riveting machines, since it is capable of use in other machines of that general class and that it is not to be limited to the specific construction shown, since it may be embodied in other forms of construction within the purview of the following claims.

What I claim is:

1. In a machine of the class described, the combination of a work support mounted for horizontal reciprocation and normally in an inoperative position, a pivotally mounted bell-crank lever operatively connected at one end to said work support, a foot treadle, a treadle rod, resilient connections between said treadle rod and the other end of said lever whereby a partial depression of said treadle moves said work support into operative position and means carried by said treadle rod whereby a further depression of said treadle starts the machine in operation.

2. In a machine of the class described, the combination of a work support mounted for horizontal reciprocation, means for holding said work support normally in an inoperative position, a pivotally mounted bell-crank lever operatively connected at one end to said work support, a foot treadle, a treadle rod, resilient connections between said treadle rod and the other end of said lever whereby a partial depression of said treadle moves said work support into operative position, means for starting the machine in operation and means carried by said treadle rod whereby a further depression of said treadle operates said starting means to start the machine in operation.

3. In a machine of the class described, the combination of a work support mounted for horizontal reciprocation, a pivotally mounted bell crank lever operatively connected at one end to said work support, a foot treadle, resilient connections between said foot treadle and the said other end of said lever including a treadle rod and a spring, said spring being of sufficient strength without distension to move said work support to operative position when said treadle is partially depressed and being distensible to permit further depression of said treadle after said work support has reached operative position, means for starting the machine in operation, means carried by said treadle rod for operating said starting means on the further depression of said treadle and means for returning said work support to inoperative position when the pressure on said treadle is released.

4. In a machine of the class described, a work support mounted for horizontal reciprocation, a pivotally mounted bell-crank lever connected at one end to said support, a foot treadle provided with a treadle rod, a spring connecting said rod and the other end of said bell-crank lever and adapted to move said work support into opera-

tive position when said treadle is partially depressed, means for starting the machine in operation, means carried by said treadle rod for operating said starting means on a further depression of said treadle rod after the work support has been moved into operative position, and a spring for raising said treadle when the pressure thereon is released to return said work support to inoperative position.

5. In a machine of the class described, a work support mounted for horizontal reciprocation, a pivotally mounted bell-crank lever connected at one end to said support, a spring for holding said work support normally in an inoperative position for receiving work, a slotted link pivotally connected to the other end of said lever, a foot treadle provided with a treadle rod, a block member secured on said rod and having a pin projecting through the slot in said link and a spring fastened at one end to the end of said pin and at its other end to said lever, said spring being of sufficient strength without distension to move said work support to operative position on a partial depression of said treadle.

6. In a machine of the class described, a work support mounted for horizontal reciprocation, a pivotally mounted lever connected at one end to said support, a spring for holding said work support normally in an inoperative position for receiving work, a slotted link pivotally connected to the other end of said lever, a foot treadle provided with a treadle rod, a block member secured on said rod and having a pin projecting through the slot in said link, a spring fastened at one end to the end of said pin and at its other end to said lever and means actuated by said block member on the depression of said treadle for starting the machine after the work support has been moved into operative position.

7. In a machine of the class described, a work support mounted for horizontal reciprocation, a pivotally mounted bell crank lever connected at one end to said support, a spring for holding said work support normally in an inoperative position for receiving work, a foot treadle, a treadle rod, a block member fastened on said treadle rod, a spring intermediate said block and said lever and means actuated by said block on the depression of said treadle for starting the machine after the work support has been moved into operative position.

8. In a machine of the class described, the combination of a work support mounted for horizontal reciprocation, a spring for holding said work support normally in an inoperative position, a bell-crank lever pivotally mounted at its angle, one end of said lever being operatively connected to said work support for reciprocating the same when said lever is turned on its pivot, a foot treadle, a treadle rod, a spring connecting the upper end of said treadle rod with the other end of said bell-crank lever, said spring being of sufficient strength on a preliminary depression of said treadle to move without distension said work support from normal inoperative position to operative position, a depending rod adapted when pulled down to start the machine in operation and means carried by said treadle rod for pulling down said starting rod to start the machine on a further depression of said treadle.

9. In a machine of the class described, the combination of a work support mounted for horizontal reciprocation, a spring for holding said work support normally in an inoperative position, a bell-crank lever pivotally mounted at its

angle, one end of said lever being operatively connected to said work support for reciprocating the same when said lever is turned on its pivot, a foot treadle, a treadle rod, a spring connecting the upper end of said treadle rod with the other end of said bell-crank lever, said spring being of sufficient strength on a preliminary depression of said treadle to move said work support from normal inoperative position to operative position, a depending rod adapted when pulled down to start the machine in operation and means, comprising a block carried by said treadle rod and a collar fastened in adjustable position on said depending rod, for pulling down said starting rod to start the machine on a further depression of said treadle.

10. In a machine of the class described, the combination of a work support mounted for horizontal reciprocation, a spring for holding 20 said work support normally in an inoperative position, a bell-crank lever pivotally mounted at its angle, one end of said lever being operatively connected to said work support for reciprocating the same when said lever is turned on its pivot, 25 a foot treadle, a treadle rod, a spring connecting the upper end of said treadle rod with the other end of said bell-crank lever, said spring being of sufficient strength on a preliminary depression of said treadle to move said work support from 30 normal inoperative position to operative position, a slotted link for guiding the connection of said spring to said rod, a depending rod adapted when pulled down to start the machine in operation and means, comprising a block carried by said 35 treadle rod and a collar fastened in adjustable position on said depending rod, for pulling down said starting rod to start the machine on a further depression of said treadle.

11. In a machine of the class described, the 40 combination of a work support mounted for hori-

zontal reciprocation, resilient means for holding said work support normally in an inoperative position, a bell-crank lever operatively connected at one end to said work support, a foot treadle, a treadle rod, resilient connections between said treadle rod and the other end of said lever whereby a partial depression of said treadle moves said work support into operative position, and means carried by said treadle rod whereby a further depression of said treadle starts the 10 machine in operation.

12. In a machine of the class described, the combination of a work support mounted for horizontal reciprocation, resilient means for holding said work support normally in an inoperative position, a bell-crank lever operatively connected at one end to said work support, a foot treadle, a treadle rod, a spring connecting said treadle rod to the other end of said lever whereby a partial depression of said treadle moves said work 20 support into operative position without distending said spring, and means carried by said treadle rod whereby a further depression of said treadle starts the machine in operation.

13. In a machine of the class described, the combination of a work support mounted for horizontal reciprocation, resilient means for holding said work support normally in an inoperative position, a bell-crank lever operatively connected at one end to said work support, a foot treadle, a 30 treadle rod, a spring connecting said treadle rod to the other end of said lever whereby a partial depression of said treadle moves said work support into operative position without distending said spring, a rod for starting the machine and means carried by said treadle rod whereby a further depression of said treadle operates said rod to start the machine in operation.

ARTHUR R. HAVENER.
